US00D838164S

(12) **United States Design Patent** (10) **Patent No.:** **US D838,164 S**
Hanchett et al. (45) **Date of Patent:** **** Jan. 15, 2019**

(54) **LOW-PROFILE COUPLER**

(71) Applicant: **Axon Enterprise, Inc.**, Scottsdale, AZ (US)

(72) Inventors: **Mark Hanchett**, Mesa, AZ (US); **John Wilson**, Phoenix, AZ (US); **Nathan Patulski**, Scottsdale, AZ (US); **William Soper**, Bristol (GB)

(73) Assignee: **AXON ENTERPRISE, INC.**, Scottsdale, AZ (US)

(**) Term: **15 Years**

(21) Appl. No.: **29/611,662**

(22) Filed: **Jul. 24, 2017**

Related U.S. Application Data

(63) Continuation of application No. 14/698,750, filed on Apr. 28, 2015, now Pat. No. 9,756,930.

(57) **CLAIM**

The ornamental design for a low-profile coupler, as shown and described.

DESCRIPTION

FIG. 1 is a perspective view of the ring showing the top, front, and the left side with the bottom oriented downward with respect to the page;

FIG. 2 is a top view with the front of the low-profile coupler;

FIG. 3 is a bottom view with the rear of the low-profile coupler;

FIG. 4 is a left view with the front of the low-profile coupler;

FIG. 5 is a right view with the front of the low-profile coupler;

FIG. 6 is a front view with the bottom of the low-profile coupler;

FIG. 7 is a rear view with the bottom of the low-profile coupler; and,

FIG. 8 is an environmental perspective view of the low-profile coupler showing the top while positioned in a cover with a portion of a base extending there-through.

The dashed lines in the drawing show environment structure and form no part of the claimed design.

1 Claim, 6 Drawing Sheets
